United States Patent Office

Des. 216,062
Patented Nov. 18, 1969

216,062

HANDBAG

Evelyn L. Domingo, 2219 Mondocino,
San Diego, Calif. 92107

Filed Apr. 10, 1968, Ser. No. 11,405

Term of patent 14 years

Int. Cl. D3—02

U.S. Cl. D87—3

Fig. 1

Fig. 2

Fig. 3

FIGURE 1 is a side elevational view of a handbag, showing my new design, the other side being similar;
FIG. 4 is a bottom plan view thereof.
I claim:
The ornamental design for a handbag, as shown and described.
